G. W. CASSIDY

ELECTRIC SWITCH

Filed March 7, 1924.

George W. Cassidy
Inventor

By his Attorneys, Dodson & Roe

UNITED STATES PATENT OFFICE.

GEORGE W. CASSIDY, OF NEW YORK, N. Y.

ELECTRIC SWITCH.

Application filed March 7, 1924. Serial No. 697,459.

To all whom it may concern:

Be it known that I, GEORGE W. CASSIDY, a citizen of the United States, residing in the city, county, and State of New York, have 5 invented a certain new and useful Improvement in Electric Switches, of which the following is a specification.

My invention relates to that class of devices which are used with lighting fixtures 10 and has for its object to provide a more convenient switch than is obtainable in any of the standard devices now employed for that purpose and has for its further object to provide a device which may be constructed 15 in such a way as to be extremely ornamental.

My means of accomplishing the foregoing objects may be more readily understood by reference to the accompanying drawings which are hereunto annexed, and which are 20 a part of this specification—

Fig. 1 is an elevation view of my device with ornamentation.

Fig. 2 is a longitudinal cross section of my device.

Fig. 3 is an elevation view showing device in closed position.

Fig. 4 is an elevation view showing device in open position.

Fig. 5 is a bottom view.

Similar reference numerals refer to similar parts throughout the entire description.

As shown in the drawings, I employ a chain pull switch 1 which is of the standard construction with the exception that the 35 chain 2 depends from the bottom 3 of the switch 1 rather than coming out through the side of the shell.

The switch 1 is provided with a cap 4 of the usual description, which is provided 40 with the usual shoulder 5 which is provided with threads in which is mounted a vertical cylindrical sleeve 6 which furnishes a conduit for the electric wires 7 and 8. This conduit 6 has slidably mounted upon it a disc 9 which has an upwardly extending sleeve 9^a attached thereto. Secured to the disc 9 is a downwardly depending arm 10 the lower end of 11 which is bent inwardly and is slotted to engage the chain 2 as illustrated.

A coil spring 13 is mounted intermediate the cap 4 and the disc 9 serving to hold the disc normally in the position shown in Fig. 3.

The conduit 6 is provided with a shoulder

14 which acts as a detent to prevent the movement of the disc 9 beyond a predetermined point.

I have found it advisable to provide a wooden mold 15 which is mounted upon the disc 9 and intermediate the detent 14 and the top of the disc 9. This mold 15 serves to provide a suitable mounting for the fabric forming the ornamental covering 16 which extends down over and encloses the actuating mechanism.

It may be found desirable to enclose this fabric in a fringe 18 where a more highly ornamental appearance is desired and to more effectually hide the mechanism of the 70 switch.

The device as thus constructed, as is apparent from the drawings, looks like an ornamental tassel.

All that is necessary in order to establish 75 the connection between the electric wires 8, so as to light the lamp, is to grasp the device, preferably by the mold 15 and pull it downwardly upon the conduit 6 to the position clearly seen in the dotted lines 80 in Fig. 4 thereby drawing the chain 2 down thus closing the switch. Upon being released the spring 13 immediately returns the disc 9 to its normal position as shown in Fig. 3. 85

When the light is to be extinguished the same operation is repeated with the result that the connection is established.

For illustrative purposes and only for that purpose, I have shown a specific form 90 of construction for the embodiment of my invention, but it should be understood that I do not limit myself to the precise details of construction shown and described, but that various changes in the same may be 95 made within the scope of my invention as described and hereinafter claimed.

Having described my invention what I regard as new and desire to secure by Letters Patent is:

1. The combination with a pull switch of a conduit mounted on said switch, a disc slidably mounted on said conduit, a downwardly depending arm secured to said disc, said arm being connected to the chain of 105 said switch, a spring intermediate the switch and the disc, a detent on said conduit to prevent the movement of said disc beyond a predetermined point.

2. The combination with a pull chain 110

- switch of a conduit mounted on said switch, a disc slidably mounted on said conduit; a depending arm secured to said disc, the lower end of said arm being adapted to engage the chain of said switch, a spring intermediate the switch and disc which holds the disc normally in an elevated position, and a detent which prevents movement of said disc beyond a predetermined point.
- 10 3. The combination with a pull chain switch, of a conduit for the electrical wires, said conduit being secured to said switch, spring actuated means slidably mounted on said conduit, means movable with said slid-
15 able means to engage the chain on said switch, and means to prevent the movement of said slid-able means beyond a predeter-
mined point.
4. The combination with a pull chain
20 switch of a conduit mounted on said switch, a disc slidably mounted on said conduit, a mold mounted on said disc, a downwardly depending arm secured to said disc, the lower end of said arm being adapted to en-
25 gage the chain of said switch, a spring inter-
mediate the switch and disc which holds the disc normally in an elevated position, and a detent which prevents movement of said disc beyond a predetermined point, the fab-

ric covering secured to said mold which con- 30
ceals said spring and switch.

5. The combination with a pull chain switch of a conduit for the electrical wires, said conduit being secured to said switch, spring actuated means slidably mounted on 35
said conduit, means movable with said slid-
able means to engage the chain on said switch means to prevent the movement of
said slid-able means beyond a predeter-
mined point, and an ornamental covering which 40
encloses the means which actuate the switch.

6. The combination with a pull chain switch, a conduit secured to said switch, spring actuated means slidably mounted on 45
said conduit means movable with said slid-
able means to engage the chain on said switch, a detent to prevent the movement of
said slid-able means beyond a predeter-
mined point.

7. The combination with a pull chain 50
switch of a tassel slidably secured thereto,
a mold on said switch, means carried by
the mold which engages the chain of the
switch, and a spring intermediate the mold
and the switch which holds the mold nor- 55
mally away from the switch.

Dated February 21, 1924.

GEORGE W. CASSIDY.
